REVERSIBLE HAIR TRIMMER

Warren M. Mansfield, Glendale, Calif., assignor,
by mesne assignments, to Cutter Corporation,
a corporation of Delaware

Application January 24, 1949, Serial No. 72,413

7 Claims. (Cl. 30—31)

1

The invention relates to a reversible hair trimmer and more particularly to a comb having an adjustable razor blade thereon, the blade being adjustable to different positions on the comb for thinning the hair, for cutting hair of different lengths, or for shaving.

An object of the present invention is to provide a hair trimmer wherein the opposite edges of a double edge razor blade are in similar operative relation respectively to two similar sets of teeth on the trimmer, whereby the trimmer may be held in one hand while employing one cutting edge of the blade to cut the hair at one side of the head while the trimmer may be held in the other hand to cut the hair at the other side of the head with the other edge of the blade, in both cases the same side of the trimmer being toward the hair.

Another object is to provide a hair trimmer having a knob which is spaced from the trimmer itself and concealed in a handle in position to be embraced by the thumb and forefinger, when held in either hand.

Another object is to provide a hair trimmer for a double edge razor blade having a mean position for thinning the hair with either cutting edge, the blade being adjustable to other positions as described above, with cooperating indicia between the blade holder and the bridge and with notations on the bridge to indicate the adjustment of the blade for its different purposes. Another object is to facilitate adjustment of the blade to correspond with the indicia and notations. Another object is to facilitate adjusting the blade in either direction by a definite amount without observing the movement of the blade or the indicia. These objects are accomplished by providing a knob having opposite sides which extend slightly beyond the opposite sides of the comb, the knob preferably being polygonal in shape with opposite flat sides whereby the operator can readily turn the knob step by step to its desired adjusted position, the indicia corresponding to positions of the knob with its outermost flat sides parallel to and slightly raised above the sides of the handle.

Another object of the invention is to provide a hair trimmer wherein the parts may be molded of plastic material and, in particular, wherein the operating knob and its shaft are held in position by cementing the comb and a bridge piece together.

Certain features disclosed but not claimed herein are disclosed and claimed in Patent 2,519,954, granted August 22, 1950, to Roy P. M. Davis, for

2

"Hair Cutting Comb," and in the Patent 2,461,444 issued February 8, 1949.

For further details of the invention reference may be made to the drawings wherein Fig. 1 is a plan view of a reversible hair trimmer according to the invention.

Fig. 2 is an enlarged end view of the left end of the trimmer of Fig. 1.

Fig. 3 is an enlarged sectional view on line 10 3—3 of Fig. 1 looking in the direction of the arrows.

Fig. 4 is an enlarged plan view, principally with the bridge removed as seen on the section line 15 4—4 of Fig. 3 looking in the direction of the arrows.

Figs. 5, 6, 7, 8 and 9 are cross sectional views on lines of the corresponding numbers in Fig. 4 looking in the direction of the respective arrows, showing the bridge in place.

20 Referring in detail to the drawings, the hair trimmer 1 is composed of four pieces of material preferably of molded plastic, namely, (1) a removable blade holder 2 and three other pieces which are molded separately, namely, (2) the 25 trimmer comb 3 and its unitary handle 4, the latter here shown in the form of an ordinary comb; (3) a bridge 5, and (4) shafts 6 and 42 having an integral knob 7 thereon. The bridge 5 and the comb 3, 4 are fixed together as described 30 later, with the knob 7 and shafts 6, 42 rotatably supported therebetween.

The trimmer comb 3 has opposite sets of teeth 9 and 10 having substantially parallel base lines, each set having alternate long and short slots, 35 like the long slot 11 and short slot 12 as shown for set 9 and similar oppositely extending long and short slots 13 and 14 as shown for set 10.

The bridge 5 and trimmer comb 3 are secured together, as later described, in spaced relation 40 to provide a blade holder recess 15 having openings 16, 17 at its opposite sides so that the blade holder 2 and a conventional double edge razor blade 18 can be adjusted, inserted or removed in a direction lengthwise of the teeth of the sets 9, 45 10, hence the blade 18 can be adjusted inwardly of the teeth of one set and outwardly of the teeth of the other set as the teeth of the sets 9, 10 project in opposite directions. The blade holder 2 has an intermediate position as shown in Fig. 1, 50 wherein the blade 18 is in position to thin the hair at either of the sets of teeth 9 or 10, as in that position the cutting edge 19 of the blade intersects all long slots like 11 in the set 9, without intersecting the short slots like 12, while the opposite cutting edge 20 intersects all long slots

like 13 but not the short slots like 14. Fig. 6 shows the blade 18 in its intermediate position with cutting edge 20 intersecting long slot 13.

The blade holder 2 is movable in either direction from its mean position shown in Figs. 1, 4, 5, 6, 7 so that the blade will move inwardly of the teeth of the one set and outwardly of the teeth of the other set. The blade holder 2 is entirely removable out through the opening 16, in order to remove an old blade and replace it with a new one. If desired, the blade holder 2 and the blade may likewise be removed through the opening 17, although in the form shown in Fig. 4, the blade holder 2 has on its outer surface at one edge thereof a slot 25 and the bridge 5 has a cooperating projection 26 to limit the movement of the blade holder 2 out through the opening 17, although the stop formed by the slot and pin 25, 26 may be omitted if desired.

The opposite sides 27, 28 of the outer end of the bridge 5 are parallel to each other and to the base lines of the teeth in the sets 9, 10 and spaced apart less than the width of the blade holder 2, whereas the inner end 31 of the bridge 5 is as wide as the trimmer. The side 27 serves as an index line for a series of indicia 29 on the holder 2. The indicia 29 are graduated according to the amount which cutting edge 19 extends beyond its mean position, over the teeth in the set 9. The side 28 serves as an index line for corresponding indicia 30 on the holder 2. Indicia 30 are similarly graduated according to the projection of cutting edge 20 from its mean position, over the teeth in the set 10. Associated with each graduation of the indicia 29, 30 is a notation as indicated at 32 in Fig. 1 on the bridge 5 to indicate the cutting relation of each edge 19, 20 of the blade 18 with its respective set of teeth 9, 10, for the various operations which the blade 18 can perform as indicated, namely, thin, cut long, cut medium, cut short, shave.

To facilitate the adjustment of the blade holder 2 to various positions corresponding to coincidence between an edge such as 27 and one of the indicia 29, the blade holder 2 is operated by a knob 7 which is molded integral with oppositely extending shafts 6, 42, the shaft 6 terminating in a pinion 43 which is molded integral with the shaft 6. The shafts 6, 42 and the pinion 43 have an axis which extends lengthwise of the handle 4 and the trimmer 3. The integral trimmer and handle 3, 4 at a point inwardly of the trimmer proper and at the inner end and center of handle 4 is molded with a semi-cylindrical bearing depression 44 while bridge 5, see Fig. 9, is molded with a supplementary semi-cylindrical bearing depression 45. The shaft 6 and pinion 43 are rotatably supported in the bearings 44, 45. The shaft 42 at the other side of knob 7 is in axial alignment with shaft 6 and is rotatably supported in a semi-cylindrical bearing depression 46 molded in the handle 4 and in a supplementary semi-cylindrical bearing depression 47 molded in the bridge 5.

Between the bearing portions 45 and 47, the bridge portion 31 has, extending therethrough an aperture 50, see Figs. 3 and 8, and opposite thereto, the handle 4 has a companion through aperture 51. The knob 7 extends through the apertures 50 and 51 so that its opposite sides extend slightly beyond the outer surfaces of the bridge 5 and handle 4. As shown in Fig. 8, the contour of knob 7 is polygonal with an even number of sides so that the sides which are opposite extend parallel to each other. The surfaces 52,

and 53 adjacent knob 7 are flat whereby the knob 7 is readily adjustable until its opposite sides are parallel with the adjacent sides of the trimmer. The blade holder 2 at its inner end has a laterally offset and inwardly facing rack 54 which is driven by the pinion 43. Opposite rack 54, the outer surface of the blade holder 2 is provided with an elongated rectangular portion 55 which serves as a shoe riding in and guided by a corresponding groove 56 on the inner face of the bridge portion 31. The rack 54 extends parallel to the teeth in the sets 9 and 10 and the shoe or guide lug 55 and its groove 56 guide the blade holder and the blade for movement lengthwise of the teeth in the sets 9, 10. The blade 18 is removably held on the holder by means of two inwardly projecting lugs 100 and 101 on the inner face of the holder. Each of the lugs 100, 101 has parallel sides as shown at 102 and 103 for lug 100 in Fig. 4, these sides extending parallel to the length of the teeth in the sets 9, 10. The lug 100 slides in a groove 104 in the trimmer, this groove extending across the length of the tooth 105 and across the length of the opposite tooth 106, while lug 101 has a similar groove 107 in the inner face of the trimmer 3. The lugs 100 and 101 and their associated grooves 104 and 107, respectively, do not assist in guiding the holder 2 and the razor blade 18 for movement as above described, as grooves 104 and 107 are wider than lugs 100 and 101, and sole guiding is accomplished by shoe 55 riding in groove 56.

The middle portion of the inner face of the comb 3 has an elongated cavity 110 between both of the sets of teeth 9 and 10 whereby the grooves 104 and 107 are discontinuous, being cut away at their middle portion due to the cavity 110. However, this does not interfere with the operation of the device, as it is guided solely by the guide lug 55 and its groove 56 while the outer end 111 of the razor blade rides on the flat face of the inner face 112 of the comb, and the inner end 113 of the blade rides on the inner flat face 114 of the comb, the cavity 110 not extending outwardly into the flat face 112 and not extending inwardly into the flat face 114.

The cavities 110, 70, 71, 72 and the recess or cavities like 115 at the opposite sides of the handle 4 hasten the cooling of the thermoplastic material when in the die and, hence, make it possible to open the die quicker and remove the molded article. The knob 7 has an annular cavity 116 for the same purpose.

By rotating knob 7 sufficiently so that the pinion arrives at the end of the rack 54, the blade holder is readily removed as above described. To facilitate reengagement of the rack 54 with the pinion 43, when inserting the blade holder 2 in the trimmer, the blade holder at its outer end has guard lugs 57 and 58 which extend beyond the cutting edges of the blade, for engagement by the finger and to prevent the finger from contacting the blade. At the inner end of the blade holder 2 there are similar guard lugs 59, 60. Coincidence of the graduations of the indicia 29 and 30 with their respective index lines formed by the sides 27 and 28, correspond to positions of knob 7 with an opposite pair of its polygonal sides parallel with the outer surfaces 52, 53, respectively, of the trimmer. As shown, the knob 7 has six flat sides although some other even number could be used. By making the knob of polygonal contour, it is possible to count the number of flat sides which pass under the finger as the knob is rotated and thereby keep a mental

note of the extent of adjustment of the razor blade, without looking at the indicia 29, 30.

In order to removably hold the knob 7 in the various positions of adjustment, one face of the knob is provided with radial notches like 61, see Fig. 8, each such notch being radial and at right angles to the adjacent side like 62, with a cooperating pair of catch lugs 63 and 64, see Fig. 3, which are in alignment for engagement with the notch like 61 and its radially opposite notch like 65. A spring is not necessary to urge the knob 7 to the right so that the notches like 61, 65 will engage the lugs 63, 64, this being accomplished without a spring, by making the minimum width of the knob recess 50—51, in a direction lengthwise of the trimmer, taking into account the fact that the lugs 63 and 64 reduce such width, substantially the same as the width of knob 7. Hence, knob 7 has some friction drag while being rotated from one notch to the next and readily stops when a notch like 61 engages one of the lugs 63, or 64 the radially opposite notch like 65 also engaging the other lug 64 or 63.

The bridge 5 is held in place on the trimmer 3 as follows. The inner end of the handle 4 is provided with a number of recesses like 70, 71, 72 to reduce the amount of plastic used and improve its flow in the mold. As will be apparent from Fig. 7, the inner face 73 of the trimmer 3 is flat and the razor blade 18 slides on it. This flat portion 73 is shown as uppermost in Fig. 4 and due to the recesses 70, 71 and 72, the flat portion 73 is a rim having opposite flat sides 74 and 75 which have outer edges lying in the contour of the teeth in the sets 9 and 10, respectively. At the right end of the flat portions 74 and 75 the handle 4 has a raised portion 76 which is flat, and between them is a pair of shoulders 77 and 78. The bridge portion 31 mates with the flat portions 74, 75, 76. The inner end of bridge portion 31 has a rectangular recess 79, see Fig. 3, for engagement with the shoulders 77 and 78 and for engagement with the flat portion 76. The shoulders 77 and 78 prevent the bridge 5 from shifting inwardly lengthwise of the trimmer. Around the aperture 50, molded integral with the bridge 5 are four lugs 80, 81, 82, 83 see Figs. 4 and 8, for engagement with corresponding recesses like 84, 85 molded in the handle 4. The blade holder 2 slides in a recess in the trimmer 3 which has an inwardly projecting lug 90, see Fig. 3, at its outer end and the bridge 5 at its outer end has an inwardly projecting portion 91 which overhangs and merges with the outer end 92 and the lug 90 of the trimmer 3. To prevent lateral shift of the outer end of the bridge, as shown in Fig. 2, it is provided with oppositely extending arms 93, 94 which fit in corresponding rectangular notches 97, 95 in the trimmer 3. Also the outer end of the trimmer 3 has an elongated U-shaped notch 96, see Fig. 4, and the outer end 91 of the bridge fits therein as shown in Fig. 4.

In assembling the parts, plastic solvent or cement is applied to the pins 80 to 83 and their corresponding recesses like 84 and to the notches 97, 95 is desired, the knob 7 is placed in the bearings 44, 46 of the handle 4 and the bridge 5 is moved into position and cemented in place, whereby the knob 7 is rotatably held in position as shown in the drawings, ready to removably receive and adjust the blade holder 2.

Various modifications may be made in the invention without departing from the spirit of the following claims.

I claim:

1. A hair trimmer comprising a comb embodying laterally spaced opposite sets of teeth having parallel base lines, a bridge on, and spaced from, said comb between said sets of teeth and providing a recess open at its opposite sides adjacent both of said opposite sets of teeth, a blade holder slidably fitting in said recess for movement lengthwise of said sets of teeth such movement causing said holder to recede with respect to the teeth of one of said sets and correspondingly advance with respect to the other of said sets of teeth, a partial bearing support disposed in said bridge and a complementary bearing support in said comb, a shaft extending lengthwise of said comb rotatably mounted in said bearing supports, a pinion in one end of said shaft, a cooperating rack on said blade holder, a guide slot for said rack in said bridge, said holder having lugs for removably receiving a razor blade, said bridge having an aperture and said comb having an opposite aperture and said shaft having a knob one side of which projects through one of said apertures and the opposite side of which projects through said other aperture.

2. A hair trimmer according to claim 1 wherein in the contour of said knob is polygonal with opposite flat sides, said blade holder having opposite sets of indicia cooperating with opposite sides of said bridge respectively and said bridge having cooperating notations indicating the cutting relation of the blade with said sets of teeth for different rotative adjustments of said knob when opposite ones of said flat sides are substantially parallel with the opposite sides of said comb.

3. A hair trimmer according to claim 1 comprising a handle longitudinally extending from said hair trimmer substantially in the plane of said sets of teeth, the tips of one of said sets of teeth lying substantially in the contour line of one side of said handle and the tips of the other set of teeth lying substantially in the contour line of the other side of said handle, said apertures and said knob being arranged inwardly beyond said hair trimmer at the inner end of said handle.

4. A cutlery comprising comb and bridge members fitting together in spaced relation and providing a blade holder recess therebetween, a bearing having a portion thereof in the inner face of each of said members, an operating knob having a shaft fitting said bearing, said members having apertures through which the opposite sides of said knob project, a razor blade holder slideable in said recess, said comb member having teeth for the blade, a pinion on said shaft and a rack on said holder for adjusting the cutting relation of the blade with said teeth.

5. Cutlery comprising comb and bridge members fitting together in spaced relation and providing a blade holder recess therebetween, said comb member having opposite sets of teeth, a blade holder slideable in said recess lengthwise of the teeth of both of said sets, aligned apertures extending through each of said members at one end of said blade holder recess, a bearing at each side of said aligned apertures, each of said bearings having a portion thereof in the inner face of each of said members, an operating knob extending at opposite sides through said apertures, said operating knob having a shaft at each side thereof, each of said shafts fitting one of said bearings, one of said shafts having

a pinion, and a cooperating rack extending transversely of said blade holder, the operation of said knob serving to shift one side of said blade holder inwardly of one of said sets of teeth and thereby shift the other edge of said blade holder outwardly of the other set of teeth.

6. Cutlery according to claim 5 wherein said rack faces inwardly of said blade holder, said blade holder having an outer face having a transverse shoe, and a cooperating transverse guide slot in said bridge member.

7. A haircutting device for use with a blade comprising in combination a comb member having interspersed long and short slots on the same edge thereof and a blade positioning member for holding a cutting edge of the blade in operating position with respect to the slots, means for retaining the two members in operative position to each other, and adjusting means for allowing the blade positioning member to be moved from a position overlying both long and short slots

with the cutting edge of the blade to a position overlying only the long slots with the cutting edge.
